UNITED STATES PATENT OFFICE.

JOSEPH BLOWER DRING, OF BOSTON, ENGLAND.

DESIGN FOR A CARTON.

Application filed August 15, 1924. Serial No. 10,468. Term of patent 14 years.

To all whom it may concern:

Be it known that I, JOSEPH BLOWER DRING, a subject of the King of Great Britain, residing at 18 Witham Bank, Boston, Lincolnshire, England, have invented a new, original, and ornamental Design for Cartons, of which the following is a specification, reference being had to the accompanying drawings, forming part thereof.

I claim:

The ornamental design for a carton, as shown.

JOSEPH BLOWER DRING.
